UNITED STATES PATENT OFFICE.

MARIANO FORTUNY, OF PARIS, FRANCE.

THEATRICAL PROPERTY.

No. 895,359.

Specification of Letters Patent. Patented Aug. 4, 1908.

Application filed April 5, 1905. Serial No. 254,035.

To all whom it may concern:

Be it known that I, MARIANO FORTUNY, a subject of the King of Spain, and residing at 29 Boulevard Berthier, Paris, in the French Republic, have invented a certain new and useful Theatrical Property, of which the following is a full, clear, and exact description, and for which I have applied for Letters Patent in France, dated April 6, 1904, No. 341,952; Austria, April 8, 1904; Germany, April 9, 1904; Hungary, April 9, 1904, No. 31,974; Russia, April 1/14, 1904.

The object of the invention is to provide a concave wall or shell in a simple and inexpensive manner and the invention consists in a pliable material, such as canvas, cloth or the like secured to a rigid structure so as to form with said structure an air tight space and means for exhausting the air from said space, whereby the pliable material will be drawn towards the walls of the said structure to form a concave surface or background. A concave shell of this description may be applied in theatrical properties to represent, for example, the sky down to the horizon or the cupola of a church or any other building. It may also be employed in the photographic art and in general in all cases where there may be required a concave background for a staging in the widest sense of the term. An arrangement of this kind may also be applied in the construction of a concave shell intended for a concert hall and, in general, of a shell having a shape such as to give or to improve acoustic effects. A hollow shell of this description may be decorated in any style; but it may also be simply painted white and receive tints by projected light or luminous projections of any kind as may frequently happen in theater craft. The shape of this hollow shell varies according to the use to which it is to be put. For instance, if it is desired to represent the sky on a theater stage, it will take the form of a quarter sphere, if necessary with suppression of certain parts and addition of other parts; these latter may be portions of spherical, cylindrical or other shaped or even plane surfaces, these modifications resulting from each particular case.

For the description of the invention, the case has been considered of the representation of the sky in a theater, and the drawings represent a concave surface, corresponding approximately with a quarter-sphere.

Figure 1 represents a perspective view of the apparatus. Fig. 2 is a similar view of

the metal skeleton alone. Figs. 3, 4 and 5 show modifications in the carrying out of the invention.

The apparatus is composed essentially of two sheets A and B (Fig. 1) of woven material such as cloth or similar fabric, the interior one A having its edges secured to a vertical rigid metallic arc *a* and to a horizontal rigid arc *b*, the outer one B being secured at its two ends to the vertical arc *c* and the horizontal arc *d*; this last sheet is moreover supported from inside by a series of bows *e f g*. All of these bows are jointed at their ends at *h* so that the arrangement resembles the hood of a carriage.

A pipe *t* (Fig. 1) connects the space enclosed between the two sheets with a suction pump *V* worked in any manner desired. When this pump is operated, the air in the annular space becomes rarefied and the pressure of the atmosphere drives these two sheets or fabrics towards one another. The internal sheet which is secured only at the two extreme arcs spreads out in the form of a regular concave surface; the other rests upon the intermediate bows between which it beds down as seen in Fig. 1, without however touching the interior surface because of the distance which separates the two cloths. Care is taken, of course, to securely anchor the vertical head arcs and the horizontal arcs.

When the apparatus is not to be used, it can be folded by means of the joints *h* of the arcs, towards the vertical arcs and by means of cables and pulleys *p p p* can be raised to the upper part of the theater.

Fig. 3 represents a second method of carrying out the invention. The interior fabric *A* is in this example also secured to a vertical arc *a* but the lower portion is simply tensioned by a series of ropes *l l' l'' l'''* fastened to the flooring.

The exterior sheet *B* is secured to a rectangular front frame *c*, to one or more intermediate frames *c'* and to an end frame *c''*. In the transverse direction, a sheet joins the head or front arc *c* with the frame *a*; similarly another sheet completely closes the end frame *c''*. Thus this arrangement forms a kind of chest or caisson. The pump *V* and the pipe *t* effect the rarefaction of the air enclosed between the two sheets. The various frames are carried upon two horizontal rails by means of rollers *R' R''* . . . which arrangement allows of closing up the apparatus

on itself by bringing the frames together after having detached the guy-ropes l , l' .

In Fig. 4 the inner sheet A is secured to two rigid arcs the one a vertical the other b horizontal; the outer sheet B forms a kind of conical or pyramidal surface having its apex at O and its base on the frame c and on the horizontal arc d . The pull exerted on the point O allows this conical surface to be tensioned sufficiently to resist the slight vacuum produced by the pump V.

In Fig. 5 it has been supposed that the outer wall was formed by the masonry of the theater itself. A represents in longitudinal section (along the axis of the theater) the sheet forming the concave vault. This sheet is stretched owing to the vacuum effected in the space H inclosed between it and the masonry walls of the stage. The pump V maintains this vacuum or lessening of pressure within the space H.

Having thus described my invention, what I claim as such and desire to secure by Letters Patent, is;—

- 25 1. A structure adapted for use as a background for theatrical or kindred purposes, consisting of a sheet of pliable material forming the background proper, a relatively rigid structure forming therewith a closed substantially air tight space, and means for exhausting the air from said space.
2. A structure adapted for use as a background for theatrical or kindred purposes, comprising a rigid structure, a piece of pliable material secured at its edges to the walls of the structure to form therewith a closed

space, the pliable material being of greater dimensions than the distance between the walls to which it is secured, and means for exhausting the air from the said space.

3. A structure adapted for use as a background for theatrical or kindred purposes, comprising a skeleton frame open at one side, an outer covering for the frame, a piece of pliable material secured to the edges of the frame and forming with the covering thereof a closed space, the piece of pliable material being of greater dimensions than the distance between the edges of the frame to which it is secured, and means for exhausting the air from the said space.

4. A structure adapted for use as a background for theatrical or kindred purpose, comprising a hood-like frame formed of a plurality of bowed rods, a piece of pliable material secured upon the outer surface of the frame and forming a covering therefor, a second piece of pliable material secured to the edges of the frame and forming with the first piece of pliable material a closed space, the second piece of pliable material being of greater dimension than the distance between the edges of the frame to which it is secured, and means for exhausting the air from the said space.

In testimony whereof, I have signed my name to this specification, in the presence of two subscribing witnesses.

MARIANO FORTUNY.
